(57) **CLAIM**

The ornamental design for a display screen comprising a compute ops management graphical user interface, as shown and described.

DESCRIPTION

FIG. 1 is a front view of a first image in a sequence of images of a display screen comprising a compute ops management graphical user interface.

FIG. 2 is a front view of a second image thereof.

FIG. 3 is a front view of a third image thereof.

FIG. 4 is a front view of a fourth image thereof.

FIG. 5 is a front view of a fifth image thereof.

FIG. 6 is a front view of a sixth image thereof.

FIG. 7 is a front view of a seventh image thereof.

FIG. 8 is a front view of a eighth image thereof.

FIG. 9 is a front view of a ninth image thereof.

FIG. 10 is a front view of a tenth image thereof; and,

FIG. 11 is a front view of an eleventh image thereof.

The graphical user interface is displayed on a portion of a display screen. The outer edge of the portion of the display screen is understood to be congruent with the outer edge of the graphical user interface as shown. The appearance of the graphical user interface sequentially transitions between the sequence of images shown in FIGS. 1-11. The process or period in which an image transitions to another forms no part of the claimed design. The broken lines depict portions of the graphical user interface which form no part of the claimed design.
